US00D685140S

(12) **United States Design Patent**
Rosenstein et al.

(10) **Patent No.:** **US D685,140 S**
(45) **Date of Patent:** **** Jun. 25, 2013**

(54) **FEED PARTITION**

(75) Inventors: **Maurice Rosenstein**, Navasota, TX (US); **Juan Moreno**, College Station, TX (US)

(73) Assignee: **ST Reproductive Technologies, LLC**, Navasota, TX (US)

(**) Term: **14 Years**

(21) Appl. No.: **29/384,300**

(22) Filed: **Jan. 28, 2011**

(51) LOC (9) Cl. **30-02**

(52) U.S. Cl.

USPC **D30/119**

(58) **Field of Classification Search**

USPC D30/114, 116, 119, 199; 119/406, 119/408-410, 452, 516, 519, 521, 522

(57) **CLAIM**

The ornamental design for a feed partition, as shown and described.

DESCRIPTION

FIG. 1 is an isometric view of a feed partition.

FIG. 2 is an isometric view thereof with a portion broken away.

FIG. 3 is a top view of the feed partition.

FIG. 4 is a bottom view of the feed partition.

FIG. 5 is a left side view thereof.

FIG. 6 is a right side view thereof.

FIG. 7 is a front view of the feed partition; and,

FIG. 8 is a back view of the feed partition.

The broken lines are for illustrative purposes only and form no part of the claimed design.

1 Claim, 7 Drawing Sheets
